His Attorney.

UNITED STATES PATENT OFFICE

2,288,285

DEHYDRATOR

James L. Knight, Erie, Pa., assignor to General Electric Company, a corporation of New York

Application April 12, 1941, Serial No. 388,281

9 Claims. (Cl. 62—89)

My invention relates to refrigerator cabinets and more particularly to dehydrating compartments or receptacles for use with refrigerator cabinets.

Certain foods as cereals and crackers, for example, are packaged to maintain the articles in a crisp condition. When the package is opened, moisture is absorbed and the contents lose their crispness and become "stale."

Accordingly, it is an object of my invention to provide means in refrigerator cabinets and the like for maintaining food in a relatively dry condition and therefore enhance the period during which such foods remain fresh or crisp.

It is a further object of my invention to provide a dehydrating compartment for use with refrigerator cabinets and the like.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing which illustrates a refrigerator cabinet embodying the features of my invention.

Referring to the drawing, I have illustrated a refrigerator cabinet 10 of the domestic type having a food storage compartment 11 defined by suitable heat insulated walls and a closure member 12. The walls of the cabinet include an inner liner 13 and an outer casing or liner 14 of relatively good heat conductive material, as a suitable metal, the space therebetween being filled with a suitable thermal insulating material 15. In order to provide refrigeration for the compartment 11, I have provided an evaporator or cooling element 16 of any suitable type, illustrated in the drawing as being arranged in the upper portion of the refrigerated food storage compartment. Inasmuch as the refrigerating apparatus forms no part of my present invention, it is not believed necessary to show the complete refrigerating system. I have illustrated a plurality of shelves 17 suitably retained in the desired positions on the walls of the compartment 11 as by shelf supports 18. I have also illustrated a cold storage receptacle 19 suitably supported immediately below the cooling element 16.

In the illustrated form of my invention the refrigerating unit including the motor compressor element is located at the rear of the lower portion of the cabinet (not shown). Toward the front of this portion of the cabinet there is provided a dehydrator compartment 20 in the form of a slidable drawer. In the illustrated form of my invention the dehydrator comprises a top or cover portion 21 having a downwardly and

inwardly turned flange 22 extending longitudinally along each edge of the cover, the inwardly turned portion of the flange serving as a supporting rail for the outwardly turned flange 23 of the slidable container 20. The cover 21 may be supported from the cabinet in any desired manner as by brackets 24 suitably secured as by welding to the cover and the cabinet frame.

The dehydrator receptacle 20 should be substantially airtight in order to minimize the leakage of moisture-carrying air into the interior of the receptacle. Therefore, the flange 22 of the cover preferably extends around the sides and rear of the receptacle. In the illustrated form of my invention, the front wall of the receptacle 20 is in the form of a closure member or panel 25 contacting the outer surface of the lower portion of the refrigerator cabinet in the closed position thereof. A handle member 26 is provided to facilitate operation of the receptacle or drawer 20. If necessary, the cover or panel portion 25 may be provided with suitable sealing means (not shown) for sealing the space between the panel member 25 and the front of the refrigerator cabinet in order to minimize the possibility of transfer of air between the interior of the receptacle 20 and the air exteriorly of the cabinet through that space.

I have provided communication between the food storage compartment and the interior of the dehydrator compartment or receptacle for permitting the passage of water vapor from the dehydrator to the compartment. In the illustrated form of my invention, this communicating means comprises a relatively long passage as a conduit formed from relatively good heat conductive material such as metal tubing, for example. The conduit is made relatively long in order to provide a substantial length thereof in good thermal engagement with the outer casing. This arrangement provides a good heat conducting path for conducting heat from the air exterior to the cabinet to the conduit 27 thereby tending to prevent any downward flow of air through the conduit 27 which helps to minimize the possibility of refrigerating the dehydrator. In other words, I have provided a thermal "trap" to assist in preventing the spilling of cold air into the receptacle. In order to minimize further the possibility of spilling cold air into the receptacle 20, I have provided the upper end of the conduit with an upwardly directed loop 28. The loop 28 is also advantageous because any condensation adjacent the end of the conduit associated with the food storage compartment cannot run down into the receptacle 20.

As is well understood, moisture contained in the air within the refrigerated compartment condenses out and is deposited on the coldest portion of the compartment, that is, the cooling ele-

ment or evaporator, appearing thereon in the form of frost. The provision of the conduit between the compartments makes it possible to utilize this action to dehydrate the air in the receptacle 20, the moisture withdrawn being deposited on the evaporator or cooling unit. To assist the above described action, the upper end of the conduit 21 preferably communicates with the food storage compartment 11 in the vicinity of the evaporator and should be disposed in such a manner that moisture dripping from the evaporator or cooling element, the walls of the compartment or any article stored therein will not collect in the communicating means or conduit.

Modifications will occur to those skilled in the art. For example, the dehydrator compartment or receptacle may be placed in any desired location. Also, while a sliding receptacle is illustrated, the dehydrator may be fixed as to position and be equipped with a door in the front wall, for example. Further, it is not necessary under all conditions and under all forms of my invention that the upwardly extending loop be provided, nor that the conduit engage the outer casing.

While I have shown a particular embodiment of my invention, I do not desire my invention to be limited to the particular construction shown and described and I intend in the appended claims to cover all modifications within the spirit and scope of my invention.

What I claim as new and desire to secure by Letters Patent of the United States is:

1. In a refrigerator having a refrigerated compartment and a cooling element disposed therein, a substantially air-tight receptacle associated with said refrigerator cabinet, and means communicating between the interior of the compartment and the interior of the receptacle for permitting the passage of water vapor from the receptacle to the refrigerated compartment, said means being constructed and arranged in such a manner as to prevent the collection therein of moisture dripping from said cooling element, the walls of said compartment, or articles stored in the compartment.

2. In a refrigerator having a refrigerated compartment and a cooling element disposed therein, a substantially air-tight receptacle associated with said refrigerator cabinet, and means including a passage communicating between the interior of the compartment and the interior of the receptacle for permitting the passage of water vapor from the receptacle to the refrigerated compartment, said passage communicating with the refrigerated compartment in the vicinity of the cooling element, the compartment end of said passage being constructed and arranged to prevent the collection therein of moisture dripping from said cooling element, the walls of said compartment, or articles stored therein.

3. In a refrigerator having a refrigerated compartment and a cooling element disposed therein, a substantially air-tight receptacle associated with said refrigerator cabinet, means communicating between the interior of the compartment and the interior of the receptacle for permitting the passage of water vapor from the receptacle to the refrigerated compartment, and means for substantially preventing the passage of cold air

from the interior of said compartment to the interior of said receptacle.

4. In a refrigerator having a refrigerated compartment and a cooling element disposed there-

5 in, a substantially air-tight receptacle associated with said refrigerator cabinet, means communicating between the interior of the compartment and the interior of the receptacle for permitting the passage of water vapor from the receptacle 10 to the refrigerated compartment, and thermal means for substantially preventing the passage of cold air between the interior of said compartment and the interior of said receptacle.

5. In a refrigerator cabinet of the type having

15 inner and outer metallic liners, a food storage compartment in said cabinet and a cooling element in said compartment, a substantially air-tight receptacle disposed lower than said cooling element, means communicating between the com-

20 partment in the vicinity of the cooling element and the interior of the receptacle, said means comprising a relatively long conduit having a substantial length thereof disposed in intimate thermal engagement with said outer liner for

25 utilizing the heat of the air exterior to the cabinet to minimize the flow of cold air from the compartment into the receptacle.

6. In a refrigerator having a refrigerated compartment and a cooling element disposed there-

30 in, a substantially air-tight receptacle associated with said refrigerator cabinet, means communicating between the interior of the compartment and the interior of the receptacle for permitting the passage of water vapor from the receptacle

35 to the refrigerated compartment, and means for substantially preventing the passage of moisture from the interior of said compartment to the interior of said receptacle.

7. In a refrigerator cabinet, a food storage

40 compartment, a cooling element disposed there-in, a substantially air-tight receptacle, means including a conduit communicating between the compartment and the interior of the receptacle, said conduit being provided with means for sub-45 stantially preventing the passage of moisture from the interior of said compartment to the interior of said receptacle.

8. In a refrigerator cabinet, a food storage

50 compartment, a cooling element disposed there-in, a substantially air-tight receptacle, means including a conduit communicating between the compartment and the interior of the receptacle, said conduit being provided with an upwardly 55 extending loop adjacent the end thereof associated with the storage compartment.

9. In a refrigerator cabinet of the type having walls defining a food storage compartment, the walls comprising inner and outer metallic liners with thermal insulation therebetween, the outer

60 liner having relatively good heat conducting characteristics, a substantially air-tight receptacle disposed below said compartment, means communicating between the compartment and the interior of the receptacle, said means comprising a relatively long conduit having a substantial length thereof in intimate thermal engagement with the outer liner and also including an upwardly extending loop adjacent the upper 65 end thereof.

70 JAMES L. KNIGHT.
